MINE CAR

Henry P. Field, Berwick, Pa., assignor to American Car and Foundry Company, New York, N. Y., a corporation of New Jersey

Application April 20, 1931, Serial No. 531,308

29 Claims. (Cl. 105—364)

This invention relates to mine cars and has for one object the provision of a car of the character described which is of low height and great lading capacity.

5 Another object of this invention is the provision of a mine car in which the car axles are arranged below the side sills of the body, and the car body includes a bottom having a central floor portion which for the greater part thereof is arranged in a plane spaced below the car axles.

10 A further object of this invention is the provision of a mine car having a body supported by and resting upon car axles, the body including body sills and a bottom having a longitudinally 15 extending central floor portion formed of a plurality of connected sections the load supporting surfaces of which are for the greater part arranged in a plane spaced below or lower than the car axles and body sills.

20 Still another object of this invention is the provision of a new and improved car bottom for mine cars.

25 A still further object of this invention is the provision of an end dump mine car having a body supported by and resting on car axles, the body including a bottom having a central floor portion and side floor portions on either side thereof; the central floor portion being a fixed lading bottom and having portions thereof arranged in a plane lower than the axles and having other portions upwardly sloping toward the dumping end of the body whereby to permit the free discharge of lading from the body upon end dumping of the car.

30 Other objects and advantages of this invention will be apparent from the following description taken in conjunction with the accompanying drawings in which:

Figure 1 is a sectional view through the car at 40 one end portion thereof.

Fig. 2 is a sectional view through the opposite end portion of the car, the said end portion showing an end gate.

Fig. 3 is an end view of the car at the gate end 45 thereof.

Fig. 4 is a sectional view on the line 4—4 of Fig. 5.

Fig. 5 is a broken top plan view of the car, certain parts being shown in section and other parts 50 being shown broken away.

Fig. 6 is a sectional view on the line 6—6, Fig. 3.

Fig. 7 is a sectional view showing a modified 55 form of wheel hood and its connection to the car body.

Fig. 8 is a sectional view showing a modified form of wheel housing and its connection to the car body, and

Fig. 9 is a sectional view similar to Fig. 6 but showing the side floor portions as being horizontally arranged in contradistinction to the sloping side floor portions shown in Fig. 6 and in Fig. 3.

Referring now more particularly to the drawings in which similar characters of reference 10 designate similar parts in the several views, the car of the present invention comprises a body indicated generally at A which is mounted on and supported by axles 2 carried by wheels 4, the body including side walls 6, a fixed end wall 8 secured to the side walls, an end gate 10 pivoted to the side walls at 12, and a bottom which is indicated generally at B.

The body is provided with side sills 14 which, as more clearly shown in Fig. 3, project into the 20 lading zone of the body and extend from end to end thereof and are secured by suitable connectors 16 to end sills 18 which latter form parts of end constructions hereinafter more specifically described. As shown clearly in Fig. 5, the 25 connectors which secure the sills to the fixed end wall 8 of the body are corner angles while the connectors at the gate end of the car are preferably gussets.

The side sills 14 are preferably bulb angles, the 30 lower flanges 19 of which are oppositely arranged and extend outwardly to serve as attaching elements for side floor portions 20 forming parts of the bottom B and arranged on each side of the central floor portion 22; said side floor portions 35 resting on the upper surfaces of the lower flanges 19 of the sills and being secured thereto by suitable fasteners such as rivets 24. In Fig. 4 the side floor portions are clearly shown as intersecting the plane of the tops of the car wheels, but this is merely by way of example as obviously the side floor portions may be substantially horizontally arranged. The side floor portions are provided 40 with openings 26 through which the wheels project and said openings are covered by wheel hoods 45 H which may assume any desired form. As examples of the construction of the wheel hoods H, several forms are shown, and in Fig. 4 the hoods have their outer edges upwardly flanged as at 50 28 to be secured to the side walls 6 by fasteners 30, while their inner edges are downwardly offset as at 32 and are fastened to the outwardly projecting flanges 34 of pressed fillers 36 secured as by fasteners 38 to the webs 40 of the side sills. 55 The ends of the housings or hoods H rest upon

and are secured to the side floor portions 20 by fasteners 42 and preferably the housings are so formed as to present a gradual slope upwardly on one side of the wheels to guide the lading toward the end gate when the car is dumped. The construction just described constitutes, in effect, a two-part wheel hood including the housing member H and the filler; the construction permitting easy separation of parts to permit replacement when desired. This construction further provides a wheel housing or hood which is reinforced or stiffened by the pressed filler member.

Fig. 7 discloses a modification of the wheel housing construction, and in this figure the side floor portions 20 are indicated as being substantially horizontal whereby they intersect the plane of the hubs of the wheels. The housing H in Fig. 7 has a flanged connection to the side walls 6 similar to that shown in Fig. 4, but the inner 10 portion of said housing is downwardly bent as at 44 and then vertically flanged as at 46 to rest against the side of the filler block 48 to which it is secured by suitable fasteners 49; the flange 46 extending to a point substantially in contact with the side floor portion 20. It is not necessary that the wheel hoods extend to the side walls 6, and as shown in Fig. 8, they may be secured by suitable 20 fasteners directly to the side floor portions 20 and to the webs of the side sills.

The sills 14 carry the load and may rest directly upon the axles 2 which are shown as square in cross section (see Figs. 1 and 2) and extend through brackets 50 secured to the lower flanges 19 of the sills by fasteners 52 and having portions 54 underlying the sills as shown more clearly in Fig. 4. The drawings are illustrative only, and obviously the axles need not be square in cross section. Further, it is not absolutely essential that sills 14 rest directly on the axles as they may be connected thereto in any suitable or desired manner. For stiffening the structure at the axles, angles 56 may be provided which may be secured to the sills by the before mentioned fasteners 52, the angles being relatively short and extending 40 only substantially the distance covered by the arms of the brackets, as shown clearly in Fig. 5.

The free edges of the side floor portions are preferably upwardly flanged as at 58 to define attaching portions for the side walls 6 which are secured thereto by suitable fasteners such as rivets or the like, and the fixed end wall 8 laps the ends of the side walls 6 and the adjacent side floor portions and is riveted thereto, as clearly shown in Fig. 5. For stiffening the body, braces 55 60 are employed which are connected to the side walls and side floor portions and extend downwardly and are connected to the sides of the central floor portion 22, as hereinafter described. At the gate end of the car a belt 62 is provided which extends along the side walls and side floor portions and under the body, as more clearly described hereinafter.

At the gate end of the car the end construction includes a Z bar 64 which extends from side to side of the body, the lower flange 66 thereof projecting outwardly to serve as a support for a bumper filler block 68 supported also by a bottom bumper plate 70 riveted to the end sill, as at 72, and extending rearwardly beyond the web 74 of the sill to furnish a supporting medium for spaced gussets 76 riveted thereto and to the upper flange 78 of said sill. As clearly shown, the lower flange 66 of the Z bar end sill extends between the side sills and a short distance therebeyond, the remainder of said lower flange being removed

and the remaining portions of the Z bar, which define an angle, are upwardly sloped toward the sides of the body (see Fig. 8) as shown at 77. The belt 62 underlies the upper flange 78 of the end sill for the entire length thereof and the ends of the side floor portions lap the belt 62 and are arranged in substantially abutting relation with the contiguous edges of the upper flange of the end sill and are connected thereto as by welding, as shown at 79. The belt 62, therefore, serves not only as a stiffening element, but also as a positive supporting medium for the ends of the side floor portions. The opposite ends of the side floor portions are supported by the turned flanges 81 of the fixed end wall 8 and are secured thereto by suitable fasteners such as rivets or the like. The bumper at the gate end of the car also includes a top plate 80 and a channel-shaped front plate 82 which laps the top and bottom plates 80 and 70, respectively; the former overlying the top flange 78 of the end sill. At the opposite end of the car the end sill comprises a channel, the upper and lower flanges 82 and 84 thereof extending outwardly, as shown clearly in Fig. 1. The fixed end wall 8 is connected to the web 86 of the channel end sill by means of the before mentioned angle connectors 16 and by cooperating gussets 88 riveted to the fixed end wall 8, the side sills and the end sill.

The lower flange 84 of the channel end sill serves as a support for a filler block 90 having a bottom cover plate 92 riveted to the lower flange 84 and a top cover plate 94 riveted to the end sill as clearly shown. A channel shaped front bumper plate 96 is provided, the flanges of which overlie the bottom and top cover plates, the bumper structure so far described being provided with an opening which receives a coupling pin 98 supported by a plate 100 upwardly flanged as at 102 and riveted at the flange to the end wall 8 and the before mentioned angles 16, the plate 100 extending from side sill to side sill and being supported by and secured to the upper flange 82 of the end sill and serving also as a connecting medium for the end wall 8 and the end sill, as will be apparent.

The central floor portion 22 is continuous from end to end of the body and, in the instance shown, is formed of a plurality of connected pan-shaped units, substantially similar in shape, and supported by the axle 2, side sills and the channel end sill at one end of the car and by the belt 62 and the before mentioned gussets 76 at the gate end of the car. While the central floor portion is shown as formed of a plurality of units, it is within the scope of the present invention to form a central floor portion of a single unit, pressed or bent, or otherwise suitably formed to the desired shape.

The central floor portion units may be termed hoppers and in the car illustrated three thereof are shown, namely, front and rear hoppers 104 and 106, respectively, and an intermediate hopper 108. The drawings disclose one embodiment of the central floor portion and the individual units thereof are formed as integral structures bent or otherwise formed to comprise a bottom 110, a vertically extending rear wall 112 and an upwardly sloping front wall 114 the forward edge portion of which is flanged as at 116 to provide a supporting surface. Formed integral with the units are side walls 118 which extend over and are connected to the webs 40 of the side sills 14, as shown clearly in Fig. 4. It is obvious that if desired the central floor portion units may be formed of connected sections or portions to define the

bottom 110, front and rear walls 114 and 112, respectively, and the beforementioned side walls 118 and the present invention is not to be considered as restricted to a hopper constructed of a single piece of material.

In the assembly of the car, the individual hoppers are of such size that the side walls 118 thereof will closely engage the webs 40 of the side sills to be secured thereto by suitable fasteners such as the rivets shown, and the rear hopper 106 has its rear wall 112 fitted against the web of the channel end sill (see Fig. 1) to be secured thereto in any desired manner. The drawings disclose the forward end of hopper 106, which, as heretofore described, is upwardly sloping, with its flange 116 resting upon and supported by the adjacent axle 2, said forward edge and the edges of the side walls 118 abutting the edges of the side walls and the edge of an attaching flange 120 formed with the rear wall 112 of hopper 108 and is welded at the abutting edges, as shown at 122. With this construction, the axles directly support the contiguous or adjacent edges of adjacent hoppers, but obviously, if desired, the said edges may be connected to supporting elements connected to the axles, said edges receiving their support from the axles. Also, the adjacent edges of adjacent hoppers may be lapped and connected, within the spirit of this invention. Hopper 108 is similar to hopper 106 with the exception that the rear wall 112 thereof is provided with the before mentioned flange 120, which flange, together with the flange 116, formed at the opposite or front end of hopper 108, and which rests on the other axle 2, supports hopper 108, as clearly shown in Fig. 2. Hopper 104 is supported by axle 2 and is connected to hopper 108 in a manner similar to the connection of the hoppers 106 and 108, and its upwardly sloping forward end 114 terminates adjacent the edge of the upper flange 78 of the Z-bar end sill and is welded thereto, as shown at 124. For giving additional support to hopper 104 the before mentioned gussets 76 are provided which underlie the upwardly sloping front end 114 of hopper 104 and are secured thereto by suitable fasteners such as the rivets shown clearly in Fig. 2. Secured to the sloping front end 114 of hopper 104 is a draw-bar 126 which extends outwardly beyond the gate 10 of the body in spaced relation to the bumper and serves to support a coupling pin 128.

The car described herein provides a body of great lading capacity having a central floor portion comprising a plurality of hopper elements having portions thereof defining means for guiding the lading toward the gate end of the car when the car is dumped, thus eliminating the use of independent axle housings such as are well known in the art, and providing a construction in which the horizontal bottom portions 110 of the hopper members may be arranged at a low level to increase the lading capacity of the car.

It is to be understood that the axles 2 are arranged below the lower flanges of the side sills, in contradistinction to a construction in which, in order to obtain increased lading capacity and an arrangement in which the central floor portion is in a plane below the axles, it has been necessary to extend the axles through the sills. The present car provides a construction in which by simply removing the bolts 52 which connect the axle brackets to the sills the body may be removed from the axles to permit replacement of parts when desired.

It is believed that the construction of the car of the present invention will be fully apparent to

those skilled in the art. The drawings disclose one embodiment of the invention, but they are for illustrative purposes only and the invention is not restricted to the specific details shown therein as obviously various changes may be made in the form and proportions of the construction shown within the scope of the appended claims without departing from the spirit of the invention.

What is claimed is:

1. In a mine car, the combination of a lading body having an end gate, end sills, side sills connected to the end sills and projecting into the lading zone of the body, car axles below the bottom portions of the sills, and a fixed lading bottom having portions thereof below the car axles and other portions inclined upwardly to partially overlap and to be supported by the car axles.

2. In a mine car, the combination of a lading body, end sills, bulb angle side sills connected to the end sills and projecting into the lading zone of the body from end to end thereof, side floor portions secured to the lower flanges of the side sills, car axles below the bottom flanges of the side sills, and a plurality of pan-shaped structures arranged between and connected to the side sills with portions of their bottoms arranged below the car axles and other portions thereof inclined upwardly to partially overlap the upper surfaces of the car axles whereby said structures are transversely supported.

3. In a mine car, a body having a central floor portion and side floor portions on each side thereof, an end gate, a Z bar end sill at the gate end of the car, said side floor portions having one end arranged substantially in abutting relation with the edge of the upper flange of the Z bar, and said central floor portion having one end upwardly inclined with its edge arranged in substantially abutting relation to the edge of the upper flange of the Z bar.

4. In a mine car, a body having a central floor portion and side floor portions on each side thereof, an end gate, a Z bar end sill at the gate end of the car, said side floor portions having one end arranged substantially in abutting relation with the edge of the upper flange of the Z bar, and said central floor portion having one end upwardly inclined with its edge arranged in substantially abutting relation to the edge of the upper flange of the Z bar, and an end belt extending across the junction defined by the abutting edges of the end sill and side floor portions and serving as a support for the ends of said side floor portions.

5. In a mine car, a body comprising side walls, a fixed end wall, an end gate and a bottom, bulb angle side sills projecting into the lading zone of the body, car axles below the bottom portions of the side sills, end sills to which the side sills are secured, said bottom comprising side floor portions secured to the lower flanges of the side sills and a central floor portion formed of connected units suspended from the side sills and each including a horizontal portion arranged in a plane lower than the car axles and having the front end thereof upwardly inclined, the ends of the inclined portions and rear end portions of adjacent units of the central floor portion being adjacently arranged over and supported by the car axles.

6. In a mine car, a body comprising side walls, a fixed end wall, an end gate and a bottom, bulb angle side sills projecting into the lading zone of the body, car axles below the bottom portions of the side sills, end sills to which the side sills are secured, said bottom comprising side floor

- portions secured to the lower flanges of the side sills and a central floor portion formed of connected units suspended from the side sills and each including a horizontal portion arranged in a plane lower than the car axles and having the front end thereof upwardly inclined, the ends of the inclined portions being welded to the rear end portions of adjacent units and the said united portions being arranged over and supported by the car axles.
7. In a mine car, a body, side sills, car axles below the bottom portion of the side sills, and a central floor portion formed of a plurality of units each comprising a pan-shaped structure having side walls lapping and secured to the side sills, a horizontal portion arranged in a plane spaced below the side sills and axles and having its forward end portion upwardly inclined and a rear end wall, the forward edges of the inclined portions and the rear edges of the rear end walls of adjacent units being contiguously arranged and welded together over the car axles.
8. In a mine car, a body, side sills, car axles below the bottom portion of the side sills, and a central floor portion formed of a plurality of units each comprising a pan-shaped structure having side walls lapping and secured to the webs of the side sills, a horizontal portion arranged in a plane spaced below the side sills and axles and having its forward end portion upwardly inclined and a rear end wall, the edges of the inclined portions and rear end walls of adjacent units being contiguously arranged and welded together over the car axles.
9. In a mine car, an axle, a bottom unit comprising a pan-shaped structure having side walls, a substantially vertical rear end wall connecting said side walls and having a flange projecting from the free edge thereof so formed and arranged as to lie over and on said axle, and a bottom wall having a portion thereof upwardly inclined.
10. In an end dump mine car, side walls, an end gate pivoted thereto, an end sill, side sills, an axle below the bottom portion of the side sills, and a pan-shaped bottom unit having a vertical rear wall with its free edge horizontally flanged to be supported by the axle and having its front wall upwardly inclined with its edge arranged in substantially abutting relation with the end sill and welded thereto.
11. In a mine car, side walls, an end gate pivoted to the side walls, a Z bar end sill having its lower flange outwardly extended, a bumper connected to the end sill and including a bottom bumper plate extending rearwardly beyond the web of the end sill, a car axle, and a bottom unit supported at one end by the axle and having its opposite end upwardly inclined with its edge arranged adjacent the edge of the upper flange of the end sill and welded thereto, and gussets secured to the bottom bumper plate, the end sill and the inclined portion of the bottom unit.
12. In a mine car, a body, side sills, car axles below the bottom portions of the side sills, and a bottom comprising pan-shaped structures secured to the webs of the side sills and having their adjacent edges arranged in substantially abutting relation over and upon the car axles whereby adjacent end portions of adjacent pan-shaped structures are directly supported by said axles, a Z bar end sill, the pan-shaped structure adjacent the Z bar end sill having its forward edge arranged contiguous to the upper flange of the end sill and welded thereto.
13. In a mine car, a body, bulb angle side sills, car axles arranged below the bottom portions of the side sills, wheels supporting said axles, and a car bottom comprising a central floor portion and side floor portions, the latter intersecting the plane of the tops of the car wheels, filler members secured to the side sills adjacent the axles, and wheel housings connected to the side walls and to said filler members.
14. In a mine car, side sills, a Z bar end sill at one end of the car, a channel end sill at the opposite end of the car, a fixed end wall, corner angles secured to the fixed end wall and to the side sills and channel end sill for connecting said fixed end wall to the end sill, side floor portions secured to the bottom flanges of the side sills whereby the latter project into the lading zone of the body from end to end thereof, and a central floor portion secured to the webs of the side sills and having portions thereof in a plane lower than the axles and other portions upwardly inclined to overlie and be supported by the axles, an end gate, the inclined portions of the central floor portion sloping upwardly toward the end gate and the inclined portion adjacent the end gate terminating adjacent the edge of the upper flange of the Z bar end sill and being welded thereto, and gussets connected to the Z bar end sill and to the central floor portion for supporting the latter adjacent the end gate.
15. A mine car floor comprising a plurality of units arranged end to end and having their adjacent end portions upwardly bent, each pair of said portions defining an axle housing, the adjacent edges of adjacent units being arranged in connected abutting relation and said adjacent end portions being so formed as to rest directly upon car axles at the abutting connected portions.
16. A mine car floor comprising a plurality of units arranged end to end with their adjacent end portions upwardly bent to define axle housings, said adjacent ends being then flanged and arranged in substantially abutting relation to define supporting portions adapted to rest upon car axles, said abutting edges being welded together.
17. In a mine car, axles, longitudinal sills arranged in a plane above and resting on the axles, and a pan shaped bottom supported by the axles and secured to the sills and having a lading supporting portion arranged in a plane spaced below the sills and axles.
18. In a mine car, axles, longitudinal sills arranged in a plane above and resting on the axles, and a car floor secured to the sills and having portions thereof arranged in planes lower than the sills and axles.
19. In a mine car, axles, longitudinal sills arranged in a plane above and resting on the axles, and a car floor secured to the sills and arranged in a plane spaced below the sills and axles.
20. In a mine car, a body comprising side walls, end walls, bulb angle side sills projecting into the lading zone of the body, car axles below the bottom portions of the side sills, and a bottom, said bottom comprising a central floor portion and side floor portions on each side thereof, said central floor portion including a plurality of units arranged end to end with their adjacent end portions deflected upwardly and arranged over and supported by said axles.
21. In a mine car, a body comprising side walls, end walls and a bottom, side sills projecting into the lading zone of the body, car axles below the bottom portions of the side sills and a bottom including a central floor portion secured to the sills

and formed of a plurality of units arranged end to end with adjacent end portions deflected from the main plane of said units and arranged over and supported by the axles.

5 22. In a mine car, a body, axles, side sills above the axles and supported thereby and projecting into the lading zone of the body, an end sill, said side sills terminating short of said end sill, means connecting the side sills and end sill, and a plurality of longitudinally aligned floor units arranged between and connected to the said sills, said units having portions thereof arranged in a plane below the axles and having their adjacent end portions upwardly deflected and connected to define 10 axle housings enclosing and supported by the axles.

23. In a mine car, the combination of a lading body having an end gate, end sills, side sills connected to the end sills, car axles arranged 20 below the bottom portions of the sills and on which the sills rest, and a stationary lading bottom having portions thereof spaced below the car axles and sills and integral vertical flanges connected to said side sills and by which the 25 bottom portions are supported.

24. In a mine car, the combination of a lading body, end sills, bulb angle side sills connected to the end sills, side floor portions secured to the lower flanges of the side sills, car 30 axles below the bottom flanges of the side sills, and a plurality of pan-shaped structures arranged between and connected to the side sills with portions of their bottoms arranged below the car axles and having vertical flanges lapping 35 and being connected to the side sills.

25. In a mine car, a body comprising side walls, end walls, bulb angle side sills, car axles below the bottom portions of the side sills and on which the side sills rest, and a bottom comprising a

central floor portion arranged in a plane spaced below the side sills and integral vertical side flanges riveted directly to said side sills.

26. In a mine car, a body comprising side walls, a fixed end wall, an end gate and a bottom, bulb angle side sills spaced above the normal plane of said bottom, car axles below bottom portions of the side sills but above the normal plane of the bottom, end sills to which the side sills are secured, said bottom comprising side 10 floor portions secured to the lower flanges of the side sills and a central floor portion formed of connected units suspended from the side sills.

27. In a mine car, side sills, a Z bar end sill at one end of the car, a channel end sill at the 15 opposite end of the car, axles, a fixed end wall, and a central floor portion secured to the webs of the side sills and having portions thereof in a plane spaced below the sills and axles and other portions upwardly inclined to overlie and be supported by the axles.

28. In a mine car, a pair of axles arranged in spaced relation, a bottom unit comprising a pan-shaped structure having side walls, a substantially vertical rear end wall connecting said side walls 25 and having a flange projecting from the free edge portion thereof so formed and arranged as to lie over and on one of said axles, and a bottom wall having a portion thereof upwardly inclined with its free edge portion arranged over 30 and on the other axle.

29. In a mine car, a body, axles, longitudinal body sills projecting into the lading zone of the body and arranged in a plane above and resting directly upon the axles, and a car floor suspended 35 from the sills and having portions thereof arranged in a plane spaced below the axles and body sills.

HENRY P. FIELD.
